UNITED STATES PATENT OFFICE.

JOHN B. HARRISON, OF CINCINNATI, OHIO.

DESIGN FOR A RING.

SPECIFICATION forming part of Design No. 13,282, dated September 5, 1882.

Application filed June 9, 1882. Term of patent 14 years.

To all whom it may concern:

Be it known that I, JOHN B. HARRISON, of Cincinnati, in the county of Hamilton and State of Ohio, have invented a new and original Design for Devotional, Engagement, or Nuptial Rings, which design is fully set forth in the following specification and accompanying drawings, in which—

Figure 1 is an edge view of a ring having thereon the design. Fig. 2 is a side view of same. Figs. 3, 4, and 5 are side and edge views.

The object of the invention is to provide a devotional, engagement, or nuptial ring.

The design in the invention is to first space off the ring, as shown in the figures, in which there is a central line, crease, or groove, A, running entirely around the ring, which is intersected with cross grooves, creases, or lines

B, or the cross-lines C may alternate, thus forming sections on each side of the central line, A. The sections may have stamped, engraved, or impressed thereon appropriate signs, figures, or characters.

What I claim is—

A ring having the annular groove or grooves, crease, line, or depression A, and the cross-lines B, and the sections thus formed numbered or figured consecutively, as shown.

In testimony that I claim the foregoing I have hereunto set my hand this 3d day of 30 June, 1882, in the presence of witnesses.

JOHN B. HARRISON.
